DRAWER SLIDE

Dudley A. Cox, Grand Rapids, Mich., assignor to
Michigan Desk Company, Grand Rapids, Mich.,
a corporation of Michigan

Application August 3, 1942, Serial No. 452,341

1 Claim. (Cl. 45—77)

This invention relates to drawer slides and is particularly adapted for so-called extension draw slides for filing cabinets and similar articles.

One of the objects of this invention is to provide a structure which may be made substantially entirely of wood, which is particularly desirable during the present times because of the shortage of steel for non-war production. Also the device provides an economical, rigid, smoothly and quietly operating structure particularly well adapted for its purpose.

The invention provides various new and useful features of construction and arrangement as hereinafter more fully described and particularly pointed out in the claim, reference being had to the accompanying drawings, in which

Fig. 1 is a perspective view of a filing cabinet showing one of the drawers removed and another drawer extended.

Fig. 2 is a perspective view of the extension supporting cradle removed from the structure.

Fig. 3 is a vertical section of one of the drawer sections of the cabinet showing the drawer fully extended and supported by the slide.

Fig. 4 is a fragmentary transverse section on the line 4—4 of Fig. 3.

Fig. 5 is a fragmentary transverse section on the line 5—5 of Fig. 3, and

Fig. 6 is a fragmentary sectional plan illustrating the mounting of one of the bearing rollers near the end of a division bar of the cabinet.

Like numbers refer to like parts in all of the figures.

The cabinet is a case having a back 1, sides 2, a top 3 and division bars 4 extending across the open front of the cabinet and dividing the drawer sections. Vertical frame members 5 are provided in the cabinet structure.

The drawers are conventional having fronts 6, sides 7 and rear ends 8. Each drawer is partially supported by a cradle having side bars 10 and transverse connecting bars 11. The cradles are slidably mounted in the cabinet on rails as hereinafter described.

Each of the side bars 10 of the cradle is provided near its end with a roller 12 mounted on a fixed axle and traversing the upper edge of a rail 13 fixed to the cabinet. The lower edge of each bar 10 rides upon a roller 14 mounted near the end of one of the division bars 4. For convenience of construction the division bars 4 are provided with a recess to receive the lower portions of the rollers 14 and a groove is formed in the upper surface of the division bar into which the

axle of the roller 14 is inserted. The rollers 12 and 14 support the downward load of the cradle and the drawer mounted thereon.

Upward extensions 10a are provided at the rear portions of the side bars 10 of the cradle and in these upward extensions longitudinal grooves 16 are formed which receive floating rollers 17 and side rails 18 fixed to the cabinet have corresponding grooves 19 formed in their lower edges to receive the upper parts of the floating rollers 17. During operation the rollers 17 traverse the grooves 16 and 19 and absorb the upward thrust of the rear ends of the cradle bars 10. Stop blocks 20 are located in the grooves 16 at the respective ends of the extensions 10a to prevent the rollers 17 leaving the grooves.

The forward upper edges of the cradle bars 10 are provided with grooves 21 to receive the floating rollers 22 and rails 23 fastened to the respective sides 7 of the drawers are provided in their lower edges with longitudinal grooves 24 which receive the upper portion of the floating rollers 22 and these rollers traversably support the downward thrust of the drawers on the side bars 10 of the cradle. Stop blocks 25 and 26 are located at the respective ends of the grooves 21 and 24 which when engaged by the rollers 22 prevent the rollers from leaving the grooves and also limit the normal outward movement of the drawers.

The rear ends of the drawers are traversably supported in either an upward or downward direction, depending upon the position of the drawer in the cabinet, by rollers 27 pivotally attached to the sides 7 of the drawers near their rear edges and these rollers 27 enter and traverse lateral grooves 28 in the vertical faces of the side rails 18. Outward movement of the cradle is normally stopped by downwardly extending stop blocks 30 on the forward cross members 11 of the cradles which strike the rear edge of a division bar 4, a piece of felt 31 preferably being interposed and attached to the division bar for quietness. When the drawer is retracted the rear surface of its front strikes the front ends of the cradle members 10 and moves the cradle also to the retracted position, a piece of felt 32 being provided at the contact surface of the drawer front for quietness.

When the drawer is fully retracted the cradle is also in retracted position and in this position the cradle is supported at its rear end on the rollers 12 and at its front end by the rollers 14 and the drawer is supported at its rear end by the rollers 27 and at its front end by the rollers

22. When the drawer is extended from this position the rollers 27 traverse the groove 28 in the rail 18 and the roller 22 traverses both the grooves 21 and 24 until the rollers 22 are stopped in their movement by the blocks 25 and 26. Further outward extension of the drawer then causes the rollers 27 to further traverse the grooves 28 and the cradles will also be extended being supported in the downward thrust by the rollers 12 and 14 and the roller 17 traversing the grooves 16 and 19 supports the upward thrust. This final extension movement is stopped by engagement of the block 30 against the felt pad 31 on the rear edge of the division member 4. In this position the rollers 14 are located midway of the cradle bar 10 and support the downward thrust of the cradle acting as fulcrums and the upward thrust of the rear end of the cradle is absorbed by the rollers 17. Also the drawers are supported in their downward thrust by the rollers 22 which act as fulcrums and the upward thrust of the rear ends are supported by the rollers 27.

If it is desired to remove the drawer from the structure after it has been extended it is merely necessary to raise its forward end sufficiently to free the rollers 22 from the stop blocks 26 whereupon the drawer may be moved outwardly removing the rollers 27 from the grooves 28. If the cradles are to be removed from the cabinet after they have been extended the forward ends are raised sufficiently to clear the stop block 30 from the division bar 4 which will permit outward movement of the cradle in which the rollers 12 leave the rails 13 and the rollers 17 remain in their grooves 16 leaving the grooves 19 in the side rails 18. Reassembling the parts consists merely in reversing the disassembling process.

This construction provides a smoothly operating strong and substantial extension drawer slide by which practically the entire length of the drawer may be extended from the cabinet but will be firmly supported in this extended position. The side bars 10 are rigidly joined in the unitary cradle structure by means of the

cross members 11 which insures their proper alignment at all times and also increases the rigidity of the structure. The device is made almost entirely of wood, excepting for such connecting means as nails or screws, and the rollers are preferably made from a compressed fibrous material which is durable and quietly operating.

The invention is defined in the appended claim and is to be considered comprehensive of all forms of structure coming within their scope.

I claim:

The combination with a cabinet having a drawer receiving opening and a drawer therefor, of a drawer slide comprising, a cradle having a pair of spaced side members located adjacent the inner sides of said cabinet, cross members extending between and rigidly connecting said side members, a roller rotatably mounted at the rear lower portion of each side member, a pair of horizontal rails respectively attached to the inner sides of said cabinet and traversed by said rollers, a second pair of horizontal rails rotatably mounted on said cabinet beneath the respective side members of said cradle and traversed by the lower edges thereof, a groove in the upper edge of the rear portion of each of said side members, a second pair of horizontal rails each attached to an inner side of said cabinet above a respective side member, a groove in the lower edge of each of said second rails, a floating roller located between each of said side members and said second rails at each side of the cabinet and traversing said grooves therein, means for slidably mounting a drawer upon and between said side members of the cradle and additional means for slidably supporting the rear end of said drawer within said cabinet comprising, lateral grooves in the vertical faces of said second rails and rollers rotatably mounted on the respective sides of said drawer near the rear end and respectively traversing said lateral grooves in said second rails.

DUDLEY A. COX.
